UNITED STATES PATENT OFFICE.

JOHN T. KENNEDY, OF WEST PATERSON BOROUGH, NEW JERSEY, ASSIGNOR OF
ONE-HALF TO FRED C. KENNEDY, OF PATERSON, NEW JERSEY.

BOX-OPERATING MECHANISM FOR LOOMS.

1,302,670.

Specification of Letters Patent.

Patented May 6, 1919.

Application filed January 12, 1918. Serial No. 211,511.

To all whom it may concern:

Be it known that I, JOHN T. KENNEDY, a citizen of the United States, residing at West Paterson borough, in the county of 5 Passaic and State of New Jersey, have invented certain new and useful Improvements in Box-Operating Mechanisms for Looms, of which the following is a specification.

- 10 This invention relates to box-operating mechanisms of the class in which the box shifting is obtained from intermeshing gear members, the driver of which has its periphery made up of adjoining toothed and blank 15 segments and the driven member of which is shiftable to clear the driver longitudinally of their axes. The invention has for its object, among others, to provide a box-operating mechanism of this class, the main part of 20 which shall be self-contained and adapted to be applied to already-existing looms by a simple manner of fastening and shall include a fixed structure or bracket of such form as at once to afford a substantial support to 25 the moving elements and limit the movements of certain of them in the direction of shifting the shiftable or driven gear member.

In the accompanying drawings,

- 30 Figure 1 is a side elevation of a box operating mechanism embodying my invention; Fig. 2 is a plan view of the essential elements;

Fig. 3 is a sectional view on line 3—3,

35 Fig. 4; and

Fig. 4 is a rear elevation.

a is the shuttle-box structure; *b* the box-lever connected therewith, and *c* a pitman connecting the box-lever with a rotary part 40 to be described.

d is the continuously rotating driving gear member fixed on a going shaft *a'* suitably journaled in the loom frame *e*, said member having the blank and toothed peripheral segments *d'* *d''*.

45 In a frame or bracket *f*, which I bolt to the side of the loom frame, is journaled a shaft *g* having affixed thereto a disk *h* against whose periphery bears a spring- 50 pressed lever *h'* which (the disk having its periphery flattened at diametrically opposite points, as shown) holds the shaft against rotation at each half-revolution thereof. The crank *i* on the outer end of the shaft is

the aforementioned part to which the pit- 55 man *c* is connected. The disk and a spline *j* on the shaft hold the latter against end- wise movement in the bearing-positions *f' f'* of the frame *f*.

On the shaft *g* is the driven gear member 60 *k* having a peripherally grooved collar *l* which normally abuts the disk *h*, being held thereagainst by the spring-pulled lever *m* which has a stud engaged in the groove of said collar; when the collar abuts the disk 65 *h* the gear member *k* is in the same plane as the gear member *d*. Member *k* is engaged with the spline *j* on the shaft, so that it rotates with but may slide on the latter out of the plane to intermesh with member *d* and 70 so as to impinge against the near bearing- portion *f'* of the bracket *f*, as shown by dotted lines in Fig. 2.

A flexible means *n*, as a wire or cord, may extend from lever *m* to a pattern or like 75 mechanism for shifting said lever contrary to its spring and hence member *k* out of the plane where it will intermesh with member *d*.

So long as member *k* is in the normal (or 80 full-line) position the member *d* will in each revolution, by its toothed part *d''*, turn member *k* a half-revolution and leave it at dwell, thus in a series of such half-turns of member *k* causing the boxes to rise and fall at regular intervals, it being understood that one of such half-turns in each instance results in pitman *c* being depressed and through lever *b* raising the boxes to bring the lower box 85 in line with the shuttle race of the batten, and that the other half-turn in each instance results in pitman *c* being raised and through lever *b* depressing the boxes to bring the upper box in line with the shuttle race. When member *k* is withdrawn to the 90 dotted-line position, Fig. 2, the boxes will remain stationary with one or the other in alignment with the shuttle-race, and this condition—effected by the pattern-mechanism acting through connection *n* and lever *m*— 95 will prevail until the pattern mechanism allows member *k* to return under the influence of the spring controlling lever *m*, whereupon the boxes will be caused by gears *d* and *k* to rise and fall again at regular intervals.

100 In view of the construction and arrangement of member *k* with respect to member *d* already pointed out, to wit, that said mem-

ber *k*, has its teeth all in the same plane as the periphery of the member *d* and arranged to successively intermesh with the gear-toothed segment thereof on successive revolutions of member *d* and (in the illustrated construction) is shiftable out of the plane where the teeth of said members will intermesh, though normally held in said plane, it will be obvious that my construction is not only simpler and more substantial and durable than others of its class heretofore devised but that where (as is generally the case) the shuttles are the most of the time called at regular intervals it reduces gear shifting (or equivalent) to the minimum. That is to say, where the general rule is, for example, black and white filling to alternate regularly on every two picks, no shifting affecting the gearing occurs at all; such shifting only occurs when the shuttle delivering one of such colors is to remain in action longer than the usual time, or when the goods being woven requires the shuttles to remain in action for irregular periods.

In the present case, where each revolution of the driving member produces a half-revolution of the driven member, the latter may have two diametrically opposed teeth short-

ened, as at *k' k'* so that the blank *d'* of member *d* will clear the same.

Having thus fully described my said invention, what I claim as new and desire to secure by Letters Patent is:—

In combination, the loom frame, a shaft journaled therein, a shuttle-box structure to be shifted, a toothed driving gear on said shaft, a bracket secured to said frame and having spaced bearing portions, and means to transmit shifting motion from said gear to said structure including a rotary member journaled parallel with the shaft in and confined by said bearing portions against longitudinal movement, a toothed driven gear splined on said member and shiftable thereon into and out of the plane of the driving gear and adapted to mesh with the latter when in said plane, the shifting movement of the driven gear being limited in one direction by said member and in the other by one of said bearing portions, means to shift said driven gear back and forth, and means to operatively connect said structure with an eccentric point of said member.

In testimony whereof I affix my signature.

JOHN T. KENNEDY.

Copies of this patent may be obtained for five cents each, by addressing the "Commissioner of Patents, Washington, D. C."

It is hereby certified that the name of the assignee in Letters Patent No. 1,302,670, granted May 6, 1919, upon the application of John T. Kennedy, of West Paterson Borough, New Jersey, for an improvement in "Box-Operating Mechanism for Looms," was erroneously written and printed as Fred C. Kennedy, whereas said name should have been written and printed as *Fred T. Kennedy*, as shown by the records of assignments in this office; and that the said Letters Patent should be read with this correction therein that the same may conform to the record of the case in the Patent Office.

Signed and sealed this 3d day of June, A. D., 1919.

[SEAL.]

J. T. NEWTON,

Commissioner of Patents.
